UNITED STATES PATENT OFFICE

156,540

LAPEL PIN OR THE LIKE

Gustave Klumpp, New York, N. Y.

Application April 8, 1949, Serial No. 1,866

Term of patent 7 years

(Cl. D45—19)

To all whom it may concern:

Be it known that I, Gustave Klumpp, a citizen of the United States of America, residing in New York, in the county of New York and State of New York, have invented a new, original, and ornamental Design for a Lapel Pin or the like, of which the following is a specification, reference being made to the accompanying drawing, forming a part thereof, in which

The dominant feature of my design is that which is shown in full lines.

I claim:

The ornamental design for a lapel pin or the like, as shown and described.

GUSTAVE KLUMPP.
